United States Patent Office

Des. 221,089
Patented July 6, 1971

221,089

CONSOLE CABINET

Harry Bergman, Glencoe, Ill., assignor to Butler
Specialty Company, Chicago, Ill.

Filed Oct. 16, 1969, Ser. No. 19,585

Term of patent 14 years

Int. Cl. D6—01

U.S. Cl. D33—19

FIG 1

FIG. 2

FIG. 1 is a front elevational view of a console cabinet showing my new design; and

FIG. 2 is a front perspective view thereof.

The back of the console cabinet is plain and unornamented.

I claim:

The ornamental design for a console cabinet, as shown and described.
